FIG. 4.

Inventor

Fred Stroud,

By-
Hiram A. Sturges,
Attorney

UNITED STATES PATENT OFFICE.

FRED STROUD, OF OMAHA, NEBRASKA, ASSIGNOR OF ONE-HALF TO HAMLIN G. ANSELL, OF OMAHA, NEBRASKA.

AMUSEMENT DEVICE.

1,386,209.

Specification of Letters Patent.

Patented Aug. 2, 1921.

Application filed June 17, 1920. Serial No. 389,565.

To all whom it may concern:

Be it known that I, FRED STROUD, a citizen of the United States, residing at Omaha, in the county of Douglas and State of Nebraska, have invented certain new and useful Improvements in Amusement Devices, of which the following is a specification.

This invention relates to an improvement in pool tables and has for its object to provide a table upon which balls may be rolled and driven by use of a cue ball and cue somewhat similar to conventional pool tables, but having such an arrangement of parts that successful playing requires a degree of skill more than ordinary.

The invention is fully described herein and its novel features are particularly pointed out in the appended claims, and is illustrated in the accompanying drawing, wherein,—

Figure 1 is a plan view of the table, the lid being omitted. Fig. 2 is a horizontal section taken longitudinally of the table to show return-ball passageways and a stop-plate. Fig. 3 is a view of the front end of the table. Fig. 4 is a view of the table in longitudinal section.

I provide a table having a horizontal base or plate 7 upon which the balls may roll, the usual resilient cushions at the sides and front end of the table being indicated at 8. Numerals 9 indicate a plurality of comparatively short, upright partitions which abut upon a rail-member α at the rear end of the table, these being suitably secured to and projecting above the plate 7. They are disposed equidistant and substantially parallel as compared with each other, parallel with the longitudinal axis of the table, and provide stalls therebetween and a pair of stalls between the side cushions and the partitions adjacent thereto, these stalls being indicated at 1', 2', 3', 4', 5' and 6'; and in each stall is formed an aperture 10 in said plate 7, said apertures being somewhat greater in diameter than the diameter of the balls.

Numerals 11 and 12 indicate lines which are provided for the plate 7, transversely thereof, and which should be readily visible, the line 11 being remote from the stalls and the line 12 being near the front end of the table.

In the present instance I have shown six stalls, but their number may be increased or decreased, if desired. At 14 are indicated balls, for convenience called object-balls,

They are numbered consecutively 1 to 6, as shown in Fig. 1, to correspond with the number and position of the stalls, and when commencing to play the game, these balls are placed on the spot-line 11, equidistant from each other at the front of the stalls, each ball being disposed a distance from the longitudinal axis of the table conforming approximately to the distance from said axis of an aperture of that particular stall at the front of which said ball is placed.

Numeral 15 indicates a cue ball, and in operation, a player may place the cue ball upon any part of the line 12 desired, and by use of a cue (not shown) the ball 15 must be driven against the balls 14 consecutively to cause them to enter the stalls, each ball 14 entering a stall at the front thereof, the ball numbered 1, for instance, being driven into the stall 1', after which the ball numbered 2 must be driven into the stall 2', the operation being continued until all of the balls 14, in succession, are driven into their corresponding stalls, the cue ball 15, in each instance, being placed by the operator upon such part of the line 12 as he may desire, and only one "shot" of said cue ball being allowed for driving an object-ball into a stall.

The game thus described is very entertaining and it will be appreciated that, for a successful operation, more than usual skill will be required. Also two persons may engage in the game, if desired, and as is obvious, various conditions or regulations, in addition to those mentioned, may be provided to cause additional interest.

The area of each aperture 10 is such that a ball 14 will pass through if it enters a stall, said ball falling upon the inclined bottom 16 of the table and being conducted by operation of gravity to the stop-plate 17 at the front end of the table.

Numerals 18 indicate apertures formed in the upright casing at the front end of the table, these apertures being designated by consecutive numbers, 1 to 6 inclusive and indicated at α , best shown in Fig. 3, said numbering corresponding to the numbering and playing positions of the balls 14.

Numerals 19 indicate parallel partitions which are provided for the bottom member 16 to provide grooves or channels 20 in which the balls may roll, each partition being disposed in the plane of a partition 9

so that each aperture 10 will be disposed in the vertical plane of a groove 20, and by this construction correct results in the playing of the game may be readily determined, for it will be understood that an object-ball, while moving swiftly upon the base or plate 7, may enter a stall which was not expected or intended, without the error being discovered, but on account of the arrangement of parts as described, said errors will be disclosed, for, if a numbered ball enters a stall not conforming to the conditions above outlined, the number of said ball will not correspond to the required number x at the front end of the table.

Numeral 21 indicates a lid adapted to prevent accumulations of dust, when closed, and when the table is in use, the lid may be elevated to rest against a wall or other support 22.

Having fully described my invention, what I claim as new and desire to secure by Letters Patent is,—

1. In an amusement device, a table rectangular in plan having apertures formed in one of its sides between its top and bottom and bearing indicating characters adjacent to said apertures, and having resilient cushions projecting above its top and three of its sides and having a rail-member projecting above its top and one of its sides, its said top being provided adjacent to the rail-member with a plurality of second apertures, said table also having its top provided transversely with lines of demarcation, a plurality of object-balls bearing indicating characters corresponding to the first named indicating characters and adapt-

ed to be disposed on one of said lines, partitions abutting upon said rail-member intermediate said second apertures and disposed parallel with the longitudinal axis of the table, inclined channels each having a part disposed below and in the plane of a second aperture and communicating with a first named aperture, and a cue-ball adapted to be disposed on a line of demarcation and to be moved for moving each object-ball to be discharged through one of said second apertures.

2. In an amusement device, a table having a plurality of numbered apertures formed in one of its sides and having a rail-member at one of its sides projecting above its top, and having a plurality of second apertures formed in its top adjacent to said rail-member, said table also having its top provided with lines disposed parallel with said rail-member, a plurality of object-balls adapted to be placed on one of said lines and bearing numbers corresponding to the numbers of the first named apertures, partitions between said second apertures abutting upon the rail-member and extending inwardly of the table, inclined conduits each having a part disposed below in the vertical plane of a second aperture, and a cue-ball adapted to have movements from one of said lines for moving the object-balls to said second apertures.

In testimony whereof, I have affixed my signature in presence of two witnesses.

FRED STROUD.
